UNITED STATES PATENT OFFICE.

THOMAS J. GILL, OF CHICAGO, ILLINOIS, ASSIGNOR OF ONE-HALF TO
WILLIAM J. COURTNEY, OF SAME PLACE.

DESIGN FOR A PLAQUE-EASEL.

SPECIFICATION forming part of Design No. 26,932, dated April 20, 1897.

Application filed March 5, 1897. Serial No. 626,142. Term of patent 14 years.

To all whom it may concern:

Be it known that I, THOMAS J. GILL, a citizen of the United States, residing in the city of Chicago, county of Cook, and State of Illinois, have invented and produced a new and useful Design for Plaque-Easels, of which the following is a specification, reference being had to the accompanying drawing, forming a part thereof.

10 Said drawing represents a perspective view of an easel embodying my novel design.

An easel embodying my novel design embraces two external longitudinally-arranged side pieces and a cross-piece which extends 15 transversely from one of said pieces to the other and is connected at its opposite ends with said pieces between the ends thereof. Said side pieces are exact duplicates as to 20 form and position and each is of curved form with reversed curves at its opposite ends and has the general form of a letter **S**. The rear end of each of said pieces is curved upwardly to form a short scroll and terminates in a slightly-enlarged end portion. That portion 25 thereof immediately adjacent to and inside of said scroll is downwardly curved, and the lower surface thereof is adapted to rest in contact with the supporting-surface. From said horizontal portion each bar is curved 30 sharply upwardly and thence gradually and

gracefully downwardly toward the front end thereof, and then forwardly and upwardly and rearwardly and downwardly, forming a scroll which terminates in a slightly-enlarged end portion, thus completing the general form 35 of an inverted letter **S**, as stated. From the upwardly-curved front end of each side piece projects a curved prong, which is forwardly, downwardly, and rearwardly curved and forms a scroll which lies in the same plane as 40 the scroll forming the end of the bar and terminates in a slightly-enlarged portion. Between the ends of each side piece and adjacent to the cross-bar which extends between the same is formed a short prong, which is 45 curved upwardly and slightly forward and forms a scroll which also lies in the vertical plane of the side pieces, said last-mentioned scroll terminating in a point at its outer end.

I claim—

50 The design for plaque-easels as shown and described.

In testimony that I claim the foregoing as my design I affix my signature in the presence of two witnesses.

THOMAS J. GILL.
